UNITED STATES PATENT OFFICE.

JACQUE C. MORRELL, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR REFINING HYDROCARBON OILS.

No Drawing.

Application filed April 27, 1923. Serial No. 635,124.

To all whom it may concern:

Be it known that I, JACQUE C. MORRELL, a citizen of the United States, residing in the city of Chicago, county of Cook, and State of Illinois, have invented certain new and useful Improvements in Processes for Refining Hydrocarbon Oils, of which the following is a specification.

This invention relates to improvements in 10 a process for refining hydrocarbon oils and refers more particularly to the refining of cracked distillates such as those produced under heat and pressure conditions resulting in the forming of aromatic distillates 15 having objectionable ingredients which must necessarily be removed before the products are marketable. The use of sodium plumbite or a solution of litharge in caustic soda is recognized as being old in the petroleum art. In conjunction with the use of these materials sulphur has been used as a precipitating agent. The use of sulphur is objectionable because sulphur is appreciably soluble in such oils and has a deleterious effect upon metals and particularly 20 motor parts with which it comes in contact.

It has been found that with certain types of oils and especially those having a content of sulphur compounds that an aqueous solution of sulphur dioxide or sulphurous acid will bring about this precipitation without introducing the deleterious effect caused by sulphur.

As a rule, the use of caustic soda containing litharge dissolved therein as desulphurizing agent has been made use of in connection with sulphuric acid refining and other refining agents. In ordinary practice the use of litharge dissolved in caustic soda 35 has followed the use of sulphuric acid, preceded it sometimes with water washes intervening. The usual procedure is to treat the oil with sulphuric acid, then water wash after allowing the sludge to settle and subsequently treat with litharge in caustic soda, sometimes preceded by a caustic wash. When the oil is treated with litharge and caustic soda compounds are formed which 40 are oftentimes difficult to remove and usually require the use of sulphur as a precipitating agent.

For reasons mentioned previously it is proposed to replace the use of sulphur by a solution of sulphur dioxide as a precipitating agent. In some cases straight run 55 gasoline is treated with the litharge and caustic solution. The present invention is applicable in any case with the aforementioned benefits.

In very rare cases the addition of a solution of hydrogen sulphide previous to the application of sulphur dioxide solution will assist in bringing about precipitation of the lead sulphide and other suspended materials. Thus the replacement by the sulphur dioxide of the sulphur serves the purpose of relieving the oil of such objectionable ingredients and precipitates which heretofore have been removed by the addition of sulphur and eliminates the objectionable feature of having sulphur which is appreciably soluble in the oil from combining therewith.

I claim as my invention:

1. Steps in a process of refining hydrocarbon oils, comprising subjecting the oil separately and individually to the action of sulphuric acid and caustic soda containing litharge, and subsequent to the subjection of the oil to the action of caustic soda containing litharge, adding sulphur dioxide to assist in the refining reaction. 75

2. Steps in a process of refining hydrocarbon oils, comprising subjecting the oil separately and individually to the action 80 of sulphuric acid and caustic soda containing litharge, and subsequent to the subjection of the oil to the action of caustic soda containing litharge, adding sulphurous acid to assist in the refining reaction. 85

3. Steps in a process of refining hydrocarbon oils, comprising subjecting the oil separately and individually to the action of sulphuric acid and caustic soda containing litharge, and subsequent to the subjection of the oil to the action of caustic soda containing litharge, introducing a solution of hydrogen sulphide, and adding sulphurous acid to assist in the refining action. 95

JACQUE C. MORRELL.
